METHOD AND APPARATUS FOR FORMING HEAVY GAUGE PIPE BLANKS FROM FLAT METAL

Lawrence H. Park, Youngstown, Ohio, assignor
to Republic Steel Corporation, Youngstown,
Ohio, a corporation of New Jersey

Application September 25, 1931, Serial No. 565,007

13 Claims. (Cl. 153—54)

This invention relates broadly to an improved pipe blank and to a method of and apparatus for forming thick flat rolled metal into pipe form. It relates more particularly to pipe blanks and a forming method therefor.

It is among the objects of this invention to provide a method of forming flat rolled metal into pipe blanks wherein the stresses set up within the walls of the blanks are reduced below a material amount and are substantially equally distributed throughout the walls thereof. It is a further object of this invention to provide a method and apparatus for forming pipe blanks wherein there is practically no elongation of the finished blanks over the lengths of flat rolled metal from which they are formed during the forming operation. Another object of this invention is to construct a pipe blank having characteristics of elasticity and ductility substantially equal to the unstressed flat rolled stock from which the blank is formed. It is a still further object of this invention to provide an apparatus which is capable of continuously forming heavy gauge, flat rolled metal into pipe blanks with little or no lineal elongation, or excessive working of the metal or creation of internal stresses which are of a material amount or of unequal distribution.

This invention contemplates and includes flat rolled metal having a thickness of about $\frac{1}{4}$ " and up to about $\frac{3}{4}$ " or somewhat thereabove in thickness and the formation of such flat metal into pipe blanks having diameters ranging from a few inches to as much as 36 inches or more. It also contemplates the provision of pipe from, blanks and material within the foregoing ranges which, when welded at its seam, may be used in pipe lines containing liquid under high pressure which pipe lines may be buried in the ground where they are subjected to varying weather conditions and ground conditions such as tendencies of the ground to shift or slide and to these and other service conditions which require a pipe having a high degree of strength and a considerable amount of ductility.

In forming flat rolled cold metal into pipe blanks of the nature just described, it is important that the forming operation wherein the metal moves endwise, particularly where carried out by a rolling operation, should be so conducted that the flat metal is formed into a pipe blank without material elongation of the flat metal, without the production of abrupt bends or kinks in the metal or the setting up in the metal of material amounts of internal stresses and, with any internal stresses, so set up, being more or less equally or uniformly distributed throughout the metal. It is important that the forming apparatus for rolling such pipe blanks from flat stock should have a sufficient number of roll passes,

with the contour of the rolls of each pass so correlated with the contour of the preceding and succeeding passes as not to change the shape of the metal too abruptly from one pass to the next and thereby to cause abrupt bends or kinking of the metal, or to require excessive power in shaping the material. Yet the roll passes should bring about the desired change in shape of the metal gradually and without introducing undesired stresses therein. It is important that means such as idler passes be provided between certain of the forming passes to maintain the transverse shape of the metal between passes, or even to bend or flex the metal transversely so it may enter the next succeeding forming pass more readily and easily. For example in forming $\frac{1}{2}$ inch thick flat metal into pipe blanks of about 16 inches in diameter the forming and retaining roll passes may satisfactorily be about twenty in number with an overall length of about 86 feet and with spaces of about 4 or 5 feet intervening between the center lines of each of the adjacent roll passes, although these numbers of passes and this overall length may be varied within rather wide limits. Further, for example, the contours of the rolls of the several passes are satisfactory when so shaped as to engage the metal in every pass at a plurality of points more or less equally spaced across the width of the metal to bend the metal throughout substantially its entire width, as for example, as shown in the accompanying drawings.

35 Figure 24 is a front elevational view of the rolls of pass H'.

Figure 25 is a front elevational view of the rolls constituting pass I'.

Figure 26 is a front elevational view of the rolls comprising pass J'.

40 Figure 27 illustrates in cross section the contour of the metal and the contour of the rolls at the successive passes of the modified mill as shown in Figures 20 and 21.

Figure 28 is a diagrammatic development of a piece of metal as it is being acted on by each successive pass in the modified forming machine.

45 For convenience of illustration and simplicity of description I have designated each successive pass through which the metal passes with a letter of the alphabet and the intermediate or holding passes are designated accordingly. With reference to Figures 1 and 2 of the drawings I have shown a plurality of cooperating roll passes A to M inclusive through which the metal moves end-

50 wise and by which it is changed while cold from a flat sheet, strip or plate into a cylindrical pipe blank having a longitudinal seam to be welded. Pass A constitutes a stand of pinch rolls which

55 is not adapted to do any forming work on the metal, but merely serves to align and drive the flat rolled metal into the succeeding forming passes. Passes B, C, D, and E are driven and are composed of opposed rolls which form the flat

60 rolled metal into a transversely curved form on arcs of decreasing radii. The passes F, G, H, and I are so constructed that the metal is worked on both sides thereof. The rolls of these passes are

65 not driven for there is sufficient drive in the first five designated passes to effect the movement of the metal therethrough. The passes designated

70 J and K bend the partially formed pipe blank into a cylindrical shape while the remaining passes L and M size and form the pipe blank into a closed cylinder. As the pipe blank leaves the last pass M the seam opens slightly due to the

resiliency of the metal. The various passes hereinbefore set forth are secured to a suitable base (not shown).

With reference to Figures 3 and 4 there is illustrated pass A or the pinch roll stand of the forming mill. This stand comprises the pinch rolls 1 and 2 which are shown in greatly enlarged scale and detail in these figures. Each of the pinch rolls comprises a roll body 3 secured to a shaft 4 having a shank 5 which is adapted to pass through and be suitably supported by roll housing 6. The roll housing 6 comprises a base 7 having suitable vertical supporting members 8 and 9 secured thereto. The supporting members 8 and 9 are adapted to support and maintain the bearing boxes 10 and 11 which receive one end of the shafts 4 on one side of the roll bodies 3 and the necks 12 on the opposing side thereof. Suitable springs 13 are provided to maintain the rolls 1 and 2 apart. The clearance between the 20 rolls, and consequently the pressure that may be exerted, is controlled by a screw-down 14 co-operating with the roll 1 and is effective against the action of the springs 13 to maintain the proper spacing of the roll 1 with respect to the lower 25 roll 2.

The rolls 1 and 2 are provided with co-operating plate engaging rings 15 and 16 respectively, disposed opposite one another for engaging and advancing the metal through the forming mill. 30 No bending of the metal is accomplished by the rolls 1 and 2, but they serve merely to positively grip the metal adjacent to the edges thereof whereby they hold the same in proper alignment and provide for the initial bending step in the 35 subsequent set of rolls. One end of each of the shafts 4 has secured thereto a coupling member 17 which is adapted to receive one end of a spindle (not shown) which will be referred to hereinafter in connection with the driving mechanism 40 for effecting the operation of the mill.

After leaving the pinch rolls 1 and 2 the flat rolled metal passes into the first set of bending rolls which is designated pass A-B in Figure 2. This pass is an intermediate pass between passes A and B and is not driven. The pass A-B comprises an upper roll 18 and a pair of frusto-conical rolls 19 and 20. These rolls are shown in detail and in enlarged scale in Figure 5. As shown in this figure the rolls 18, 19, and 20 do not actually grip or pinch the metal, but besides 50 retaining the metal in the shape given to it by the preceding forming pass serve to flex or slightly bend the metal by supporting the metal adjacent its marginal edges on the rolls 19 and 20 and exerting a vertical pressure midway between these two rolls and centrally of the metal by the roll 18. The surfaces of the rolls 18, 19 and 20 are so shaped as to cause the metal to be 55 bent or flexed so as to enter the next pass readily, smoothly and without requiring excessive force to drive it into and through such pass.

The roll 18 is rotatably mounted by means of roller bearings on a shaft 21 and is held thereon similarly to rolls 19 and 20 described hereafter. The rolls 19 and 20 are rotatably mounted on a shaft 22 provided with a pair of fixed collars 23. Co-operating with each of these collars 23 is a plate 24 adapted to be positioned adjacent suitable roller bearing means 25 contained within a portion of each roll 19 and 20. Similar roller bearing means 26 are provided adjacent the outer face of each roll 19 and 20. These latter bearing means are held in position by plates co-operat- 70 75 75

ing with the collars 27 which are rigidly positioned on the shaft 22. The rolls 18, 19 and 20 are held against movement axially of the shafts 21 and 22, but are free to rotate on such shafts

5 by reason of the provision of the respective bearing means 25 and 26. The respective rolls 18, 19, and 20 may be removed from the shafts by removing the collars 27 and 28 if so desired. The rolls 18, 19 and 20 are idler rolls and their rotation is derived from the moving metal passing between them.

The ends of shafts 21 and 22 are similarly mounted, being rigidly positioned in suitable eccentrics 29 and 33 adjacent each end thereof, the latter being journaled in vertically slidable bearing boxes 31 and separated and supported vertically by means of slidable spacing blocks 32 and 33. The bearing boxes 31 and spacing blocks 32 and 33 are in turn supported in a housing frame 34, which is adapted to be secured through bolts 35 to the vertical members of the housings of passes A and B, Figure 2.

Each of the eccentrics 30 has an annular projecting hub 36 to which is externally keyed a worm gear 37. Connected with bearing box 31 are bearing members 38 wherein are journaled worms 39 which mesh with the worm gears 37. Each of the worms 39 is provided with squared ends 40 to receive a wrench to turn the same. Rotation of the respective worms 39 causes rotation of the worm gears 37 and eccentrics 30 which in turn are effective in raising or lowering the roll shafts 21 and 22 and the rolls disposed thereon are accordingly adjusted. After leaving the rolls 18, 19, and 20 of the intermediate pass A-B the metal passes between upper convex forming rolls 41 (Figure 6) and a lower concave roll 42. The upper roll is so formed as to contact with the metal throughout its entire width while the lower roll is slightly recessed at the center so that the metal is gripped over only two relatively wide areas between the concave and the convex rolls.

The housing 43 which supports the rolls 41 and 42 is secured to a base 44 by bolts 45. It is generally similar in construction to the housing for the pinch rolls 1 and 2 and is also similar to the housing of the succeeding passes C, D and E. There are provided lower stationary bearing boxes 46 and upper floating bearing boxes 47 vertically slidable in the roll housing and resiliently held apart by a plurality of springs 48. The rolls are provided with suitable driving connections 49 which connect with spindles and driving mechanism (not shown). The necks 50 of the shafts 51 and 52 upon which the rolls 41 and 42 respectively are secured are journaled in suitable roller bearings 53 housed in the bearing boxes 46 and 47. A screw-down 52' is provided, the same being threaded through a sleeve 54 in a cross member 55 connected with the top of the roll housing through bars 56 and wedges 57.

The gear wheel 58 is driven through the medium of the gears 59, 60' and 61'; the last mentioned gear being mounted on one end of a shaft 62' supported in a suitable bracket 63' and provided with a squared end 64' by means of which the gear wheel 58 may be manually operated. The lower extremity of the shaft 59 is unthreaded in a bore 53' of the yoke member 61 having laterally extending arms 62, each of which is provided with a bearing portion 63 adapted to set within a suitable recess provided in the upper bearing boxes 47. The apparatus herein provided is adapted to maintain equal adjustment

on the bearing boxes at all times and further to compensate for any discrepancies in the thickness of the metal passing between the rolls 41 and 42.

In passing from the rolls 41 and 42 of pass B the metal is engaged by a second set of idler rolls 64 and 65 of pass B-C (Figure 2).

This pass is similar in structure to pass A-B and is supported from the housings of passes B and C (Figure 2). The rolls thereof are similar to the idler rolls of pass A-B; the contour thereof corresponding to the natural flow of the metal as it reaches them. These rolls do not appreciably assist in the bending of the metal but merely hold the metal as it comes from pass B and prepares it to enter pass C, Figure 13.

Pass C (Figure 7) constitutes the next pass of the mill, and receives the metal from the idler rolls 64 and 65. This pass constitutes an upper forming roll 66 and a plurality of bottom or supporting rolls 67, 68, and 69. The upper roll 66 is similar to the roll 41 but of greater peripheral curvature. The bottom roll has disposed on each side thereof the idler rolls 68 and 69 which assist this roll in forming the flat rolled metal. The latter rolls 68 and 69 contact with the edges of the metal in its passage between them and roll 66. The construction herein disclosed embodies many economic features in that it makes unnecessary the use of a single roll which would engage the entire outer surfaces of the metal of such great widths as are used to form pipe blanks of especially large diameters. The idlers 68 and 69 are mounted on angularly disposed shafts carried in bearing brackets 71 and 72 respectively; the latter being rigidly secured to the housing 73 upon the opposite sides thereof. The rolls 66 and 67 are mounted on shafts 74 and 75 respectively. These shafts have their extremities journaled in suitable bearing boxes 76 and 77 which are resiliently held apart by springs 78 in the manner similar to that disclosed and described in pass B (Figure 6).

The housing which carries the first passes A to E inclusive of the forming mill are substantially identical in each case, the contour of the rolls being the only essentially different feature. It will be noted that as the metal passes from one set of rolls to the next the portions thereof which are gripped by the respective rolls are progressively greater distances from the center line of the metal. This provides for the smooth substantially continuous bending of the metal. It will be noted that the sets of rolls are relatively close together and are of a relatively great number. Because of the fact that the sets of rolls are relatively closely spaced, the metal is not given an independent abrupt deformation by any set of forming rolls, as the several passes are so formed, that as the metal advances through the forming means the bending occurs smoothly progressively and gradually, the close spacing of the rolls assisting in bringing about this result.

It will be observed by references to Figures 1 and 2 that beginning with the pass A the metal passes alternately through stands of driven rolls and stands of idlers. The driven forming rolls are mounted on horizontal shafts and derive their power from a motor 79 through a driving connection shown diagrammatically in Figure 1. They serve to form the metal transversely substantially on an arc, the cord of which is horizontal. The idlers which alternate with the driven rolls are mounted on inclined shafts and act more particularly on the edges of the metal to cause

such edges to assume substantially the form of continuations of the arc formed by the driven rolls. It is desirable to use idlers adjacent to the edge of the metal, as the force to be applied to the metal at such portions is in a direction inclined to the horizontal. It is much more difficult to mount the driven rolls angularly with respect to the horizontal than to so mount the idler rolls. The idler rolls can be conveniently mounted immediately adjacent the driven rolls so that the driven and idler rolls co-operate to act on the metal at a single pass.

As the metal passes from pass C comprising the forming rolls 66 and 67 it enters pass C—D (Figure 8) comprising two oppositely disposed pairs of rolls, each consisting of an upper roll 85 and a lower roll 86, the latter having a co-operating roll 87 which engages the center of the flat rolled metal on the outside. By the time the metal has reached these rolls it has been bent sufficiently that its lateral edges have begun to assume positions extending generally outwardly and upwardly, and the portions of the metal adjacent such edges are gripped by the respective pair of idler rolls 85 and 86. The rolls 85 and 86 have convex and concave surfaces respectively which co-operate in gripping the contour of the metal. The axis of the respective rolls 85 and 86 is disposed angularly with respect to the horizontal, thus providing for a firm gripping of the metal adjacent its edges between forming members properly disposed thereagainst at opposite points, even though the metal has begun to assume a distinct and very well-defined curvature.

Referring more particularly to Figure 8 there is provided a supporting frame 89 connected with the adjacent roll stands of passes C and D by means of bolts 90. Disposed midway of the cross-head 91 of the supporting frame there is suspended a bearing frame 92 having two bearing brackets 93 and 94 supported thereby. The brackets 93 and 94 carry respectively the shafts 95 and 96 upon which are journalled the rolls 85 in suitable bearing members 97. These rolls are permanently secured in position and engage the inner side of the metal at it passes therebetween.

The supporting frame 89 carries a pair of oppositely disposed stub shafts 98 on each of which is pivotally mounted an arm 99 which carries a bracket 100. The bracket 100 is of suitable yoke formation and has secured in the opposing parts of the yoke member a shaft 101 upon which is journalled the roll 86 and suitable bearing members 102. The rolls 86 mounted on the shafts 101 engage substantially the same portion of one side of the metal adjacent to the edges thereof. The lower extremity of the supporting arms 99 contains a trunnioned nut 99' which is threaded on the threaded portion of the adjusting shaft 103. The shaft 103 has right and left hand threads, hence, rotation of the shaft 103 is adapted to move the lower parts of the arms 99 inwardly or outwardly simultaneously to provide an adjusting means for varying the pressure on the metal. Adjacent the lower rolls 86 and suitably bolted to the supporting member 89 is a bracket 105 having a yoke member 106 disposed thereon which in turn carries shaft 107 upon which is journalled the roll 87.

From the roll stand C—D the metal passes through pass D which is similar in construction to pass C and is illustrated in Figure 9. This pass is similar to the hereinabove described pass C with the exception that the curvatures of the rolls are greater, to be effective in the continuous

forming of the metal. With reference to Figure 9 this pass comprises an upper forming roll 108 and a plurality of bottom or supporting rolls 109, 110, and 111. The rolls 108 and 109 are secured on shafts 112 and 113 respectively, the outer ends of such shafts being journalled in suitable bearing boxes 114 and 115. A coupling member 116 is secured to one end of each of the shafts 112 and 113 for engaging with a suitable driving means (not shown) to effect rotative movement to the rolls 108 and 109. The pairs of bearing boxes 114 and 115 are spaced apart and resiliently held in such position by a plurality of springs 117 carried by the lower bearing boxes of each pair. The idler rolls 110 and 111 are rotatably mounted on the inclined shafts 118 and 119 respectively carried by suitable bracket members 119' secured to the opposite sides of the pass housing.

From the pass D the metal passes through a set of idler rolls D—E (Figure 1) identical in construction to the pass C—D described in Figure 8; the main difference being that the shafts upon which rolls 85 and 86 of this pass are mounted are inclined at a greater angle to the horizontal to effect the continuous flow of metal from the flat to tubular form. From this pass the metal passes through the forming rolls of pass E. This pass is similar in structural detail to that shown in Figures 7 and 9 which constitute passes C and D of the mill. The contours of the rolls are so designed as to conform with the profile of the metal at this point in its transition as is shown in Figure 18 of the drawings.

Referring now to Figure 10 there is illustrated pass F which constitutes the next succeeding pass 35 of the forming mill and comprises a stand of idlers having a frame 280 to which is connected by bolts 281 a bearing yoke 282 carrying a lower supporting and guiding roll 283. The frame 280 is bolted to a suitable table 284 (Figure 2). Connected with the frame 280 are spaced outward extensions 285 converging at the top to support a bearing frame 286. The frame 286 has a pair of spaced cylindrical recesses 287, each adapted to receive a thrust bearing 288 and radial bearings 289 which, rotatably support through shaft 290 one of a pair of co-operating inside rolls 291. A retaining cover 292 having downwardly extending retaining members 293 is adapted to maintain the bearings in operative relation upon the bearing 288.

Each of the respective rolls 291 comprises an annular relatively flattened portion 294 and relatively curved metal forming portion 295 and 295'. The relatively flattened portion 294 of the respective rolls contact and roll against each other whereby the necessary re-action for resisting the pressure exerted thru the outside rolls herein-after described is provided. The portion of the rolls which is adapted to contact and roll against each other is made substantially cylindrical as compared with the adjoining portions of the roll in order that the rolls may have a substantial area of mutual contact, thereby distributing the wear due to the contact between the rolls and the length of time during which the rolls will remain in proper contact with each other, and in proper adjustment with respect to the metal being formed. The lower extremities of the shafts 290 upon which the rolls 291 are journalled are secured together below such rolls by a plate 296. Respective extensions 285 of the frame 280 are provided with apertures 297 through which pass shafts 298 carrying outer supporting roll arms 299. Each of such arms 299 is provided with a 75

trunnioned nut 127 internally threaded and engaging threads 128 and 128' respectively, the same being right and left hand on a horizontal adjusting rod 129 having wrench engaging means 5 130 disposed on the opposing ends thereof. Suitable locking means 131 is provided to hold the rod against rotation when the desired adjustment of the roll arms 299 has been obtained.

Each of the arms 299 is provided with a bearing yoke 132 in which is mounted for rotation an outside forming roll 133. The axes of the respective outside forming rolls are parallel and also parallel to the axes of the shafts 290 upon which are mounted the inside forming rolls 291. The 10 contour of the rolls 133 is formed to co-operate with the contour of the rolls 291. The metal engaging portion of each roll is adapted to lie opposite the corresponding portion of the opposite roll engaging the opposite side of the metal. The 15 metal supporting and guiding roll 283 maintains the advancing metal in the proper position to be acted upon by the rolls 133 and 291. The peripheral metal engaging surface of the roll 283 is designed to conform substantially with the metal at 20 the lower portion thereof as it reaches the stand of idler rolls thereby assisting in continuing the smooth bending of the metal in its unrestricted transition from flat to tubular form. The supporting arms 299 are adapted to be so adjusted 25 and positioned that the pressure exerted on the respective rolls 291 and 133 on both sides of the metal are substantially equal. Thus the rolls in 30 these passes co-operate to insure guiding of the metal in the desired line without skewing or exerting any substantial force tending to move the metal transversely.

The succeeding passes G, H, and I (Figure 2) are constructed similarly to the pass F above described. The respective rolls of these passes however, are designed to progressively act on the metal as it is bent in the desired smooth and gradual transition from flat to tubular form. As the lateral edges of the metal are bent upwardly and inwardly, the inside rolls co-operate with the corresponding designed outside rolls to provide the necessary gripping action to set the metal.

As the metal passes from pass I as shown best in Figure 18 the opposed edges have begun to close in at the top. The metal is then conducted through passes J and K of the mill disclosed in Figure 2, and illustrated in enlarged detail in Figure 11.

Pass J comprises a pair of oppositely disposed driven rolls 134 and 135 adapted to co-operate with a pair of inside rolls 136. All of these rolls are supported on a structure 137. The roll structure 137 is adapted to support two oppositely disposed roll carriers 138 and 139. These roll carriers are slidably mounted upon the bed of the roll structure 137. The roll carriers 138 and 139 are identical in structure and each comprises a yoke member 140, extending arms 141 and 142 in which are disposed suitable bearing members 143 which receive the opposing ends of a vertical shaft 144. The shaft 144 has keyed thereto the roll 134. The lower end of the shaft is tapered and receives a bevel gear 145 which meshes with a gear 146 splined on a horizontal driving shaft 147. The driving shaft 147 is journaled in suitable bearing members 148 carried by the opposite sides of the roll structure 137. The gear 146 is 50 slidable on the shaft 147 to compensate for any adjustment or changing of the rolls 134 and 135. Similarly the roll 135 is disposed on a vertical shaft 150, the opposing ends of which are jour-

naled in bearing boxes 151 and 152. The lower end of the shaft 150 has secured thereto the bevel gear 153 which co-operates with the bevel gear 154 splined on the shaft 147.

The upper members of the roll housing 137 are secured together by a crosshead 155 through wedges 156. The crosshead 155 is adapted to support the laterally extending member 157 which has depending from the mid-point thereof a bracket 158 which supports the roll cage 159 within which is disposed the internal rolls 136. Intermediate the base of the roll carriers 138 and 139 is disposed a supporting member 160, the upper end thereof having disposed thereon a yoke member 161 within which is journaled the roll 162. This roll is adapted to engage the bottom 15 of the metal as it passes through the pass.

Adjustment of the rolls 134 and 135 is effected through a yoke member 163 which is internally threaded to receive screws 164 and 164' which co-operate with the roll carrier 139 as at 165 to provide suitable lateral sliding movement of such roll carrier in the pass housing.

Passes J and K are substantially identical in structure with the exception that in pass K the inside rolls 136 and the supporting mechanism therefor have been omitted and in lieu thereof is used a top roll having a fin or enlarged center portion for the purpose of performing some slight forming of the edges of the metal, (see Figure 18). This top roll is housed substantially the same as the bottom roll except that such housing is supported by crosshead 155, provided with a suitable screw adjustment for adjusting the top roll.

As the metal travels from the stand of driven rolls of pass J to the stand of driven rolls of pass K it is passed through pass J-K (Figure 18), best shown by Figures 12 and 13 and is engaged by a pair of idler rolls 166 which are supported on a plate 168 which is in turn secured to the frame of the succeeding pass K by suitable bolts 169. 40 Connected to the plate 168 by bolts 170 is a bracket 171 having a horizontal projection 172 integrally formed therewith.

Integrally formed with and disposed adjacent the lower part of the plate is a horizontal projection 173 parallel to and below the projection 172. The projection 173 is provided with a pair of oppositely disposed bosses 174 having an internally threaded sleeve for the reception of a jack screw 175. Each respective jack screw has 50 integrally formed therewith a spindle 176, the upper end of which is slidably journaled in the projection 172. The extremity of the spindle 176 is squared for the reception of a wrench.

Journaled on the stub shaft 177 carried by the 55 projection 173 is a spur gear 178 which meshes with the gears 179 disposed on the jack screws 175. Rotation of either spindle 176 will cause such spindle by reason of its jack screw to move vertically. Due to the gearing between the two jack screws 60 the spindles will each partake of a correspondingly vertical movement. This provision insures that the two spindles will always be in proper co-operative relation regardless of their vertical movement.

Rotatably carried by each spindle 176 and resting on the gears 179 is a sleeve 180 having upper and lower parallel extending arms 181 and 182 respectively forming a bearing yoke for a shaft 183 carrying one of the rolls 166. Each of 70 the arms 181 carries a yoke comprising upper and lower arms 184 and 185. Carried by each yoke through upper and lower trunnions is an internally threaded hub 186.

The respective hubs 186 are adapted to pivot and are maintained substantially co-axial with respect to each other, (Figure 12) and the screw threads of the respective hubs are of opposite hand. Threaded into the respective hubs is an adjusting rod 187 provided at one end with wrench receiving portion 187'. Rotation of the rod 187 in one direction causes the respective hubs 186 and consequently the respective rolls 166 to move pivotally about the axes of the respective spindles 176 and toward each other and the operation of the rod in an opposite direction will cause the rolls to move pivotally away from each other. It will be seen therefore that the rolls 166 may be thus adjusted both vertically and horizontally toward and away from each other, the means for vertical adjustment always insuring that the rolls will remain at the same height and the means for horizontal adjustment insuring that the movement of the respective rolls toward and away from the center line of the forming machine will be equal.

By the time the bent metal has passed through the rolls of pass K the edges are fairly close to each other, but as yet no work has been done to positively align the edges or bend them into their final position. This step in the forming operation is effected in the stand of idler rolls which immediately follows pass K and designated pass K-L illustrated in enlarged detail in Figures 14, 15, and 18.

Referring now to Figures 14 and 15 there is provided a stationary mounted outside roll 188 and co-operating therewith is adjustably mounted, outside roll 189. Adjustment of the upper roll 189 is provided for through its supporting frame 189' to which is connected a screw 190 co-operating with raising and lowering worm gear 191 and worm 192. The metal is adapted to be engaged between the rolls 188 and 189, the roll 189 being adapted to straddle the cleft between the edges of the bent metal and to co-operate with the inside rolls 193 and 194 presently to be described, to further set the metal in its described smooth transition from flat to tubular form. The metal by this time has attained almost a complete tubular form.

The opposed edges of the metal are almost in contact between the rolls 188 and 189, and on account of the position of the roll 189, it would be practically impossible to support the inside rolls 194 and 193 by means extending through the cleft of the bent metal directly opposite the rolls. The support provided for the inside rolls comprises a thin plate 195 connected with the housing of pass K-L by bolts 196 and which passes through the cleft in the bent metal to the left, viewing Figure 15, of the rolls 188 and 189 and consequently at a place where the opposed edges of the metal are somewhat farther apart than they are between the vertically disposed rolls. Within the confines of the bent metal there is connected to the plate 195 by bolts 197 a generally longitudinally extending plate 198 carrying intermediate its ends a roll cage 199 having oppositely disposed side members 200 (Figure 14) which are secured to the plate 198 and carrying shafts 201 upon which are rotatably mounted the inside rolls 193 and 194. These rolls are of substantially the same diameter, the lower roll being recessed to receive the peripheral surface of the upper roll. The principal function of the lower roll in this case is to transmit pressure from the outside roll and through the metal to the opposing outside roll.

The rolls of stand K-L are supported in a housing 202 which carries a frame 203 composed of oppositely disposed side pieces 204. The lower extremities of the respective side pieces 204 are brought close together and provided with bosses 205 in which is mounted a pin 206. Mounted for rotation upon the pin 206 through suitable roller bearings 207 is the lower roll 188 of this stand. It will be apparent from the construction herein disclosed that the lower roll 188 is not adjustable in its position.

At their upper extremities the respective side pieces 204 are connected together and with the filler block 208 by bolts 209. The filler block 208 is provided with a substantially central circular opening in which is mounted for rotation on suitable roller bearing means a nut 210. The nut 210 comprises a lower enlarged portion 211 and has connected with its upper end the worm gear 191. The worm gear is keyed to the nut by a key 212. The two are maintained in axial alignment by a bolt 213 passing through a washer 214 and into the nut, the washer engaging the upper surface of the worm gear 191. The worm 192 is provided for engagement with the worm gear 191, the worm being mounted on a shaft 215 journaled in suitable bearings 216. The jack screw 190 connected to the yoke 189' is threaded in the nut 210. The yoke 189' has downwardly extending arms 216' in which is mounted a pin 217. Mounted for rotation upon the pin 217 through suitable roller bearing means 218 is the roll 189. The yoke 189' is guided for vertical sliding movement by guide means 219 provided on the inner surfaces of the respective side plates 204 and 35 suitably co-operating with appropriate guide members 220 provided on the outer surface of the yoke member 189'. By such means the yoke is held against lateral or rotative movement but vertical movement thereof is provided for in 40 order that the distance between the respective rolls 188 and 189 may be adjusted.

The jack screw 190 is pinned to the yoke 189' so that upon rotation of the worm gear 191 and nut connected therewith, the yoke carrying the 45 upper roll 189 will be raised or lowered. Such yoke is effectively maintained in desired adjusted position by reason of the worm and worm gear connection. Lateral support for the pipe blank in this stand is provided by oppositely disposed 50 guides 201 secured to the side members 204, thus placing the guides between the rolls 188 and 189. It is understood that the guides are contoured to coincide with the pipe blank at this point.

The combination of the inside and outside rolls 55 which has been described makes it possible to engage the thickness of the metal at directly opposite points to set the same in the desired smooth transition from flat to substantially tubular form, almost to the very point at which the 60 opposite edges of the metal meet each other.

As the bent metal passes from the stand of idler rolls K-L the opposite edges of the metal are so close to each other that by the time the metal engages the succeeding set of rolls the edges are 65 substantially in contact. The succeeding set of rolls is shown in greatly enlarged scale and detail in Figure 16 and designated pass L of the forming mill. This roll pass comprises three substantially similar forming rolls 221, 222, and 223 arranged 70 to engage the outside of the metal throughout substantially 360 degrees of its periphery. Each of the rolls 221, 222 and 223 has a concave metal engaging surface which is formed in cross section substantially on an arc of a circle whose diameter 75

is the external diameter of the bent metal at the point of contact. Each roll covers substantially 120 degrees of the periphery of the bent metal and the respective rolls are arranged with their axes 5 forming a substantially equilateral triangle about the bent metal so that the pressure exerted thereon by the rolls is distributed throughout the entire periphery of the metal.

The roll 223 is driven through driving connections 224 and the rolls 221 and 222 are idlers. The roll 223 comprises a body portion 225 keyed to a shaft 226 having necks 227 carrying radial bearings 228 similar to the radial bearings heretofore described. It is mounted in a roll housing 229 connected with the main frame 229 by bolts 230. The housing 229 has oppositely disposed cylindrical bearings 231 in each of which is journaled a shaft 232 pivotally carrying upstanding frame members 234. Each frame member 234 has at its 10 upper extremity an extension 235 suitably recessed at 236. The roll housing 229 has a crosshead portion 237 lying substantially between the extensions 235 of the respective frame members 234 and provided with oppositely disposed hubs 238 substantially in alignment with the respective recesses 236. Springs 239 are interposed between the respective hubs 238 and the extensions 235 and enter respective recesses 236, whereby to resiliently hold the upper portion of the respective frame members outwardly away from the crosshead portion 237 of the housing.

Disposed parallel with the crosshead portion 237 and supported therefrom is an adjusting rod 240. The rod 240 is threaded at its opposite extremities 35 as at 241, and each extremity is provided with a wrench receiving portion 242. Each of the frame members 234 somewhat below portion 235 thereof, contains a trunnioned nut 243 through which the adjusting rod 240 is threaded. Each frame member has a recess 244 snugly receiving the corresponding trunnioned nut 243 so that the nut is prevented from turning with respect to the frame member. The respective portions 241 of the adjusting rod 240 are oppositely threaded so that when the rod is rotated in one direction the respective frame members 234 move outwardly away from each other through the action of the respective springs 238, but when the rod is rotated in the opposite direction the nuts 243 bear against the respective frame members 234 to move them inwardly or toward each other in opposition to the springs 238. A lock nut 245 is threaded over the adjusting rod 240 and located on each side of a keeper 246 whereby to maintain the parts 40 in adjusted position. Each lock nut is provided with wrench sockets. The keeper 246 is attached rigidly to the crosshead 237 by means of bolts 246'.

By the mechanism just described the respective frame members 234 may be maintained in the desired adjusted position for a purpose which will presently become apparent. Each of the frame members 234 is provided adjacent the upper end thereof with U-shaped portions 247 disposed at an angle with the open ends of the U-shaped portions turned inwardly toward each other. The legs of the U-shaped portions terminate in spaced bearing portions 248 which are adapted to support a shaft 249, having threaded extremities that project through perforations in the radial wall of each bearing portion and receive nuts which may be drawn down against the walls of each bearing portion to prevent rotation of the shaft, it being understood that the rolls 221 and 222 are rotatably mounted on bearings encompassing the mid-portion 45 of their respective shafts.

The respective rolls 221 and 222 are mounted for free rotation on their respective shafts and co-operate with the driven roll 223 to effect substantially the final state in the bent metal. The metal emerges from the set of rolls 221, 222, and 5 223 in substantially perfect tubular form. The opposite edges of the metal are substantially in contact and the metal in cross section is a perfect circle. Passing from this set of rolls heretofore mentioned the formed pipe blank passes through 10 the last set of forming rolls M, which set is similar to the set described in Figure 16 and is illustrated in enlarged detail in Figure 17. The last stand of rolls comprises a top roll 250 and a pair of angularly disposed lower rolls 251 and 252. 15 The upper roll 250 is driven through the driving connection 254 and the rolls 251 and 252 are idlers. The rolls of this pass are positioned in reverse relation to the rolls shown in Figure 16, that is to say, the axis of the roll shafts form an 20 equilateral triangle with the apex pointing downwardly rather than upwardly as in Figure 16. The roll 250 comprises a body portion 255 keyed to a shaft 256 having necks 257 which are journaled in suitable bearings 258, the latter being 25 disposed in bearing boxes 259, which are in turn supported from the crosshead 260 of the roll housing 261. The crosshead 260 has laterally extending bosses 262 which are adapted to carry bearings 263 within which is journaled the shaft 264. 30 Pivotedly mounted on the shaft 264 and suspended therefrom are frame members 265 which are adapted to support the idler rolls 251 and 252. The lower extremities of the frame members 265 are recessed at 266 to receive a trunnioned nut 35 267. An adjusting rod 268 extends between the frame members 265 and co-operates with the nuts 267 disposed thereon. The trunnioned nuts 267 are in turn threaded to receive the threaded ends of the adjusting rod 268. Lock nuts 269 are 40 adapted to maintain the ends of the frame members 265 in adjusted position. Intermediate the opposing ends of the frame members 265 is a U-shaped recess 270 in the form of a yoke member, the opposing arms of the yoke member are adapted to receive and support a shaft 271 upon which is rotatably mounted the rolls 251 through suitable bearing members. The adjustment of the rolls of pass M is substantially identical to that of pass L. The contour of the rolls taken as a 45 whole are adapted to contact with substantially 360 degrees of the periphery of the bent metal as it is passing therethrough.

Passing from the forming machine the formed metal is adapted to be ejected on to a suitable 55 transfer device, (not shown), by which it is conveyed to the welding apparatus. After the formed metal has left the forming machine it might have a slight tendency, due to the natural spring of metal, for the opposing edges to move apart. However, inasmuch as the metal has been formed and set as a suitable perfect pipe blank while the edges are in contact any slight springing apart has no detrimental effect on the form and the pipe blank can be tightly held with the 60 edges together as it passes through the welding machine in order to form a welded pipe.

Figures 18, 19, and 19a serve to show the manner in which the metal changes form from the flat to a tubular shape. In Figure 18 various 70 spaced cross sections of the metal at the time it passes through the various roll passes is shown. These cross sections are described by the letters which were assigned to the hereinabove mentioned roll passes. In Figure 19 is shown one- 75

half of the contour of the metal at each roll pass from the pinch roll pass A, where the metal is flat, through the roll pass L where the metal is a completed cylinder. This view also shows the 5 relative positions of the bottom and edges of the metal at each roll pass with respect to the horizontal plane of the metal in the pinch rolls.

Figure 19a illustrates the side elevation of the half blank shown in Figure 19 with the bottom 10 and edges of the metal at each pass positioned as shown in Figure 19. A line, designated as X-axis and positioned parallel to the horizontal plane A—A of Figure 19 but tangent to the bottom of the cylindrical blank of Figure 19 is shown on Figure 19a. A line designated as Y-axis is taken perpendicular to the X-axis at the point where the X-axis is tangent to the blank. The intersection of the X and Y axes is designated O. The path of the bottom-most portion 15 of the metal in the progress of the metal through the forming zone is represented by the line R on Figure 19a which is an exponential parabolic curve. Comparison of Figures 19 and 19a will confirm the foregoing statement. For example, 20 the vertical distance of the bottom of the metal at pass L below the horizontal plane A—A on Figure 19 is the same as from O on line R to the horizontal line A—A on Figure 19a. All other vertical distances on Figure 19a are similarly 25 represented on Figure 19. The side edges likewise occupy the same positions on Figures 19 and 19a.

Figure 19b, which is a top plan view of the half blank of Figure 19, shows the theoretical line S of one edge of the blank bent from flat metal 30 at one end to a cylinder at the other end. In Figure 19b lines A—A and L—O' designate respectively the vertical plane through the flat end of the flat metal, and the vertical plane through the cylindrical end of the blank. The several passes 35 of Figure 19 are correspondingly designated and located on Figure 19b. The points on curve S represent the edge of the metal at each pass. These points are located at distances from line A—A which are respectively the distances from the vertical plane passing through the center of 40 a formed cylinder along line A—A to the intersection therewith of a vertical plane passing through the edge at the pass in question, all on Figure 19. For example, the edge of the metal 45 at pass D on Figure 19b is spaced apart from line A—A by a distance equal to that from the vertical plane through the center of the cylinder of Figure 19 to a vertical line through points D on that figure, the distance being measured on line 50 A—A. Similarly the distance of D from line A on Figure 19b is the difference between distance A—A on Figure 19 and the distance of D to the vertical plane through the center of the cylinder. Referring to Figure 19b the space between 55 lines S and R represent the top of the metal, while the space between lines S and T represent the bottom of the metal on the outside of the tubular blank.

Figure 19 shows in dotted line T the locus of 60 points equidistant from the edge and center of the metal at the several passes. This curve T is made by bisecting the curves on Figure 19 representing the various passes and then connecting such mid-points. This curve T as shown on Figure 19a is formed by locating on each roll pass 65 a point which is as far from the X-axis as the mid-point of the corresponding pass line is perpendicularly distant from the vertical center line of the blank in Figure 19. Similarly line 70 D of Figure 19 is shown on Figure 19b the dis-

tances of the points on the pass lines from the vertical center line of the cylinder blank being the same as those in Figure 19a from the X-axis.

5 Referring to Figure 19b it will be noted that the line S representing the path of one edge of the metal as that of a sine curve that is symmetrical about an X-axis taken lengthwise through the middle of the half strip A—A and also about a Y-axis taken halfway between the flat strip end and the cylindrical end.

10 In forming blanks in accordance with the teachings of this invention the curve R (Fig. 19a) representing the bottom of the metal as it passes through the forming zone may be expressed mathematically as an exponential parabolic 15 curve of a certain order. This fact will be readily appreciated by one who is skilled in the art. The curve T of Figures 19, 19a, and 19b is a parabolic curve of a higher order than that of curve R representing the bottom of the metal as is shown by 20 Figure 19a.

25 In practicing this invention the metal as it enters the machine is approximately at a point sixty-six hundredths times the diameter of the finished pipe above the axis of the finished pipe 30 as it is being ejected from the machine. The respective elevations of the metal with respect to such axis are clearly denoted in Figure 19. The sets of rolls are designed in position to carry the metal through smooth transition to effect bending and setting of metal in substantially tubular form without imparting to it any longitudinal stretching or undesirable stresses.

35 In the modified forming mill as illustrated in Figures 20 and 21, each successive pass through which the metal passes is designated by a letter of the alphabet and the intermediate passes designated accordingly. Referring to the drawings I have shown a plurality of co-operating roll passes A' to J' inclusive. Pass A' constitutes a 40 stand of pinch rolls which are adapted to align and drive the metal into the succeeding forming pass. No forming of the metal is executed in this pass. Passes B' to J' inclusive are driven and are composed of vertically opposed rolls 45 which form the flat rolled metal into complete tubular form. The latter two passes I' and J' size and form the pipe blank into a perfect cylinder. The intermediate passes are utilized primarily as holding passes between the forming passes, but 50 are intended to act upon the edges of the metal and to assist the metal on its gradual and continuous transition from a flat to tubular form. The rolls of pass I' are adapted to grip the metal and abut the edges thereof against the depending 55 flange in the center of the upper roll which aligns and squares the edges of the metal. The rolls of pass J' grip the pipe blank and in addition to sizing it into a perfect cylinder match the edges thereof in perfect alignment preparatory to 60 welding. As the pipe blank leaves the last pass J' the same is adapted to slightly spring open due to the resiliency of the metal. The various passes as herein set forth are supported and bolted to a suitable base (not shown). The pinch rolls as 65 illustrated by pass A' of Figure 21 are identical to those shown in Figures 3 and 4 and previously described. The metal then enters the intermediate pass A'—B' which is substantially the same as described and illustrated by Figure 5.

70 Pass B', the next successive pass is substantially the same as shown in Figure 6. The pass B'—C' receives the metal from pass B' which is similar to the previous intermediate pass A'—B' except that the contour of the rolls, impart more curva- 75

ture to the metal. Pass C' (Figure 22) constitutes the next pass of the mill and receives the metal from the intermediate pass B'-C'. This pass includes an upper forming roll 300 and a lower supporting roll 301, mounted on shafts 302 and 303 respectively, which are carried by bearings supported in a housing substantially as shown and described for Figure 7. The upper roll of this pass is similar to the upper roll of pass 5 B', but of greater peripheral curvature. The metal then enters the intermediate pass C'-D' which corresponds in structure and operation to Figure 8 of the preferred embodiment. Pass D' receives the metal from the intermediate pass 10 C'-D', between the upper forming roll 304 and the lower supporting roll 305, which are mounted on shafts 306 and 307 respectively. These shafts are mounted at their ends in bearing and supported by a housing substantially as illustrated by 15 Figure 9. The next intermediate pass D'-E' is substantially the same as pass C'-D' except the disposition of the rolls are such that greater curvature of the metal is obtained. Passes E', F', and G' each comprises an upper forming roll and a bottom supporting roll, similar in construction and operation to the preceding pass D', with the exception that the curvature of the rolls increases 20 accordingly as the successive passes progress toward the finished pipe blank. Likewise the intermediate passes E'-F', F'-G', H'-I', and I'-J' are substantially identical in structure and operation, and are similar to that shown in Figure 25 13 of the preferred embodiment, the variations lie in the relative size and contour of the rolls, the rolls of pass E'-F' being larger and of a greater radius, the size of the rolls and the radius 30 gradually diminishing until the pass I'-J' is reached which is shown to have practically formed the metal into a complete cylinder. Pass H' (Figure 24) consists of an upper forming roll 308 and a lower forming roll 311. The forming surface 309 of the upper roll is narrower than any of the preceding rolls and is adapted to enter the partially formed pipe blank through the opening between the edges thereof. Grooves 312 are disposed adjacent either side of the surface 309, terminating in annular flanges 310 adjacent the ends of the roll. These flanges are adapted to bear on the outer surface of the pipe blank near its ends 35 as at 313. Pass I', (Figure 25) includes upper and lower forming rolls 314 and 315 respectively. These rolls are intended to size the pipe blank and square up the edges thereof preparatory to the final sizing operation and succeeding welding 40 operation. An annular extending flange 316 is disposed in the center of the upper roll. On either side of the forming surfaces of the rolls, flat portions 317 and 318 are arranged in stepped relation to interlock and to insure proper alignment 45 between the rolls. Pass J' (Figure 26) includes a pair of forming rolls 319 and 320 respectively, adapted to properly size the pipe blank into perfect cylindrical shape, and present the open seam in the proper position to the welding apparatus. 50 These rolls are similar to those in the preceding pass, including the stepped flanges 321 and 322 on either side of the forming surfaces, but the upper roll of this pass does not contain an extending flange about the center of the forming surface. From the foregoing it will be seen that the modification departs from the preferred embodiment in number and contour of the rolls only. The housings for supporting all roll passes 55 are the same as the first five passes of the preferred form of mill. Figures 27 and 28 are dia-

grammatic illustrations depicting the manner in which the metal changes form from the flat to a pipe blank. Figure 27 shows the curvature of the metal in cross section and the rolls at each successive pass. These illustrations are designated by the letters which were assigned to the previously mentioned roll passes. The respective elevations of the metal with respect to its axis is clearly denoted in Figure 28. The various sets of rolls are designed in position to carry the metal through 10 smooth transition to effect bending and setting of the metal in substantially tubular form without imparting to it any longitudinal stretching or undesirable stresses. It will also be seen from the foregoing that the results of the modified mill 15 will produce a pipe blank equally as free from internal strains and stresses and free from elongation as the mill shown in the preferred embodiment, the same being accomplished by a considerable less number of passes. 20

While I have described the illustrated embodiment of my invention in some particularity, obviously many modifications and variations will readily occur to those skilled in the art, and I do not, therefore, limit myself to the precise 25 details shown and described, but claim as my invention all the embodiments thereof coming within the scope of the appended claims.

I claim:

1. A process of forming metal tubing comprising bending a flat strip of metal longitudinally to a cylinder having parallel seam edges by bringing the edges together progressively over a distance of at least twenty-five times the tubing diameter while gradually curving the bottom of 30 the blank away from the initial plane of the strip to bring the completed seam between that plane and the bottom of the blank, thereby maintaining initial axial lengths of the strip unchanged in extent throughout the forming of 35 the tubing.

2. A process of forming metal tubing comprising bending a flat strip of metal longitudinally to a cylinder having parallel seam edges by bringing the edges together progressively over a distance of at least twenty-five times the tubing 40 diameter while gradually curving the bottom of the blank below the initial plane of the strip to produce a completed seam lying between that plane and the bottom of the blank, and approximately 45 0.16 the tubing diameter from the plane, thereby maintaining initial axial lengths of the strip unchanged in extent throughout the forming of the tubing.

3. A process of forming metal tubing comprising bending a flat strip of metal longitudinally to a cylinder having parallel seam edges by bringing the edges together progressively over a distance at least twenty-five times the tubing diameter while gradually curving the bottom of the 50 blank away from the initial plane of the strip to form the completed tube wholly on one side of and with the completed seam adjacent to said plane. 55

4. A process of forming metal tubing comprising bending a flat strip of metal at approximately room temperature longitudinally to a cylinder having parallel seam edges by bringing the edges together progressively over a distance of at least 55 twenty-five times the tubing diameter while gradually curving the bottom of the blank away from the initial plane of the strip to bring the completed seam between that plane and the bottom of the blank, thereby maintaining initial 60 70 75

axial length of the strip unchanged in extent throughout the forming of the tubing.

5. A process of forming metal tubing comprising bending a flat strip of metal at approximately room temperature longitudinally to a cylinder having parallel seam edges by bringing the edges together progressively over a distance of at least twenty-five times the tubing diameter while gradually curving the bottom of the blank below 10 the initial plane of the strip to produce a completed seam lying between that plane and the bottom of the blank, and approximately 0.16 the tubing diameter from the plane, thereby maintaining initial axial lengths of the strip unchanged in extent throughout the forming of the tubing.

6. A process of forming metal tubing comprising bending a flat strip of metal at approximately room temperature longitudinally to a cylinder having parallel seam edges by bringing the edges together progressively over a distance at least twenty-five times the tubing diameter while gradually curving the bottom of the blank away from the initial plane of the strip to form the completed tube wholly on one side of and with the completed seam adjacent to said plane.

7. A process of forming metal tubing comprising bending a flat strip of metal to a cylinder having parallel seam edges by bringing the edges of the strip together progressively over a longitudinal distance of at least twenty-five times the diameter of the cylinder, while gradually bending the bottom of the strip longitudinally away from its initial plane along an exponential parabolic curve, and thereby preventing substantial stretching of the metal axially.

8. A process of forming metal tubing comprising bending a flat strip of metal to a cylinder having parallel seam edges by bending the strip transversely to bring the seam edges together progressively over a longitudinal distance at least 25 times the cylinder diameter and in curves maintaining the perimeter of the forming tube substantially equal to the original width of the strip away from its initial plane along an exponential parabolic curve, and thereby preventing substantial stretching of the metal along its neutral longitudinal and circumferential axes.

9. A process of forming metal tubing comprising bending a flat strip of metal longitudinally and progressively below the initial plane of the flat strip along an exponential parabolic curve, while bending the strip transversely and progressively to bring the edges together along 180° of a sine curve between planes transverse to the completed seam and the end of the flat strip, and in curves maintaining the periphery at all points between the end of the flat strip and the completed cylinder substantially equal to the width of the initial strip, and thereby continuously forming the cylinder while preventing substantial stretching of the metal with respect to its neutral longitudinal and transverse axes.

10. A process of forming metal tubing comprising bending a flat strip of metal longitudinally and progressively below the initial plane of the flat strip along an exponential parabolic curve, while bending the strip transversely and progressively to bring the edges together along 180° of a sine curve between planes transverse to

the completed seam and the end of the flat strip while maintaining the periphery at all points between the end of the flat strip and the completed cylinder substantially equal to the width of the initial strip, and bending the side walls of the forming cylinder along an exponential parabolic curve of higher order than that of the bottom of the strip between the plane transverse to the completed seam and the point where the edge of the strip passes beyond the formed side walls in 10 moving along said sine curve and thereby continuously forming the cylinder while preventing substantial stretching of the metal with respect to its neutral longitudinal and circumferential axes.

11. In a tube forming mill for progressively bending a flat strip of metal to a cylinder having parallel seam edges, a series of bending passes having individually differing curved working faces, the sides of consecutive passes progressively approaching a vertical plane through the middle of the passes, the length of the arc or working face of each pass being substantially equal to the original width of the flat strip, the mid-point of the bottom of successive passes being progressively removed below the initial plane of the flat strip supplied to the mill so that a line connecting said points forms an exponential parabolic curve, and the passes being disposed to bring the edges of the strip progressively together 25 to form the completed cylinder over a distance at least equal to twenty-five times the cylinder diameter.

12. In a tube forming mill for progressively bending a flat strip of metal to a cylinder having parallel seam edges, a series of bending passes and individually differing curved working faces, the length of the arc or working face of each pass being substantially equal to the original width of the flat strip, the mid-points of the bottoms of consecutive passes being progressively removed below the initial plane of the flat strip passed to the mill so that a line connecting said mid-points forms an exponential parabolic curve, the size of consecutive passes progressively approaching the middle plane of the passes with their upper edges positioned along 180° of a sine curve lying between the end of the flat strip and the completed seam, and the passes being disposed to bring the edges of the strip progressively together to form the completed cylinder over a distance at least equal to twenty-five times the cylinder diameter.

13. The process of making pipe blanks which includes the steps of moving an elongated, rectangular piece of flat metal endwise into a shaping zone whose length is at least twenty five times the diameter of the desired pipe blank, and, while moving said piece thru said zone, progressively changing the contour of said piece to that of a cylinder with a longitudinal seam gap by progressively moving the longitudinal central portion of the piece in one direction away from the plane of entry of the piece into said zone, and, at successive points spaced apart along said zone as the piece proceeds therethrough, curving the metal in another direction transversely thruout substantially its full width on arcs of successively smaller radii.

CERTIFICATE OF CORRECTION.

Patent No. 2,012,795.

August 27, 1935.

LAWRENCE H. PARK.

It is hereby certified that error appears in the printed specification of the above numbered patent requiring correction as follows: Page 10, first column, line 45, claim 8, after "strip" insert the comma and words , while gradually bending the bottom of the strip; and that the said Letters Patent should be read with this correction therein that the same may conform to the record of the case in the Patent Office.

Signed and sealed this 24th day of September, A. D. 1935
